UNITED STATES PATENT OFFICE

ANTHONY E. DAVIS AND JOHN N. INMAN, JR., OF PHILADELPHIA, PENNSYLVANIA

RADIATOR BRACKET

Application filed January 17, 1928. Serial No. 247,331.

In radiator brackets of the types which are used to support radiators on the wall of a room or building, they have been constructed in such a manner that it is necessary for a dealer to carry in stock not only brackets of different sizes for different types of radiators but also to carry in stock different sizes of radiator supporting cradles, tie rods and other detail parts of the bracket construction.

One object of this invention is to devise a novel radiator bracket which can be employed as a standard for all of the different sizes of radiators now in use and wherein the radiator is supported in a novel manner by the bracket.

With the above and other objects in view as will hereinafter more clearly appear, our invention comprehends a novel construction and arrangement of a radiator bracket.

It further comprehends a novel construction of a radiator bracket having a novel construction and arrangement of a body portion provided with radiator aligning means and a novel construction of an adjustable supporting plate adapted to pass between juxtaposed radiator columns, the radiator having attached to it a carrying member which is detachably mounted on the radiator supporting member of the bracket.

It further comprehends a novel radiator bracket having a supporting plate which is provided at its upper end with a tapered slot opening through its top face and adapted to receive a carrying member clamped to the radiator so that the radiator can be easily and quickly assembled with respect to the bracket and readily removed from the bracket whenever desired.

It further comprehends a novel construction of a radiator bracket having a body portion adapted to be fixed to the wall and provided with a bar adapted to receive a supporting bolt on which a novel construction of a radiator supporting member is vertically adjustable.

It further comprehends novel clamping means.

Other novel features of construction and

advantages will hereinafter appear in the detailed description and appended claims.

For the purpose of illustrating our invention, we have shown in the accompanying drawings a preferred embodiment of it, which, in practice, will give satisfactory and reliable results. It is, however, to be understood that this embodiment is typical only, and the various instrumentalities of which our invention consists can be variously arranged and organized, and the invention is not limited to the exact arrangement and organization of these instrumentalities as herein set forth.

Figure 1 is an end elevation of a radiator bracket and assembled radiator with the supporting wall shown in section.

Figure 2 is a front elevation of the radiator bracket.

Figure 3 is a top plan view of the radiator bracket.

Figure 4 is a section on line 4—4 of Figure 3.

Figure 5 is a front elevation of the radiator clamp.

Similar numerals of reference indicate corresponding parts.

Referring to the drawings:

1 designates the body portion of a radiator bracket embodying our invention. The body portion is in the form of a longitudinally extending bar having apertures 2 adapted to receive the fastening devices 3 which secure the body portion with respect to a wall 4.

The body 1 has secured to it a channel shaped supporting member 5 preferably of the same width as the bar of the body portion 1, having an upper laterally deflected arm 6 and a lower laterally deflected arm 7, each of which are apertured to receive and guide a threaded bolt 8, the head of which rests upon the upper arm 6.

10 designates a radiator supporting member or cradle which is in the form of a plate having its rear marginal portion deflected upon itself to form a sleeve 11. The supporting member 10 is cut away as at 12 to form a seat for a nut 13 and also to prevent the relative rotation of the nut 13 and the member 100.

10. The upper edge of the member 10 has opening through it a recess or slot 14, opposite walls of which diverge upwardly in order to adapt it to receive a radiator carrying member 15 in the form, as illustrated, of a plate 18 clamped to the radiator 16 by means of a clamping bolt 17 in threaded engagement with said plate 15.

10 The radiator supporting member 5 is rigidly connected to the body portion 1 by means of rivets 19 or equivalent fastening devices. The body portion 1 has secured to it by means of a fastening device 20, one flange of an angle 21, the laterally extending flange of which 15 forms a radiator aligning member.

In the use of a radiator bracket embodying our invention the radiator carrying member 15 is clamped to the radiator preferably at the upper portion of the radiator.

20 The body portion 1 of the radiator bracket is secured to the wall and the bolt 8 can be adjusted prior to or subsequently to the placing of the radiator in position. The radiator is raised into position so that the radiator supporting member 10 will extend between juxtaposed columns at the rear of the radiator and is then lowered to permit the member 15 to be seated in the recess 14. It will be apparent from Figures 1 and 5 that 30 the carrying member 15 contacts with the arches of juxtaposed tubes, so that it contacts with and carries the arches of juxtaposed radiator sections. The clamping bolt 17 is only of use in holding the carrying member 35 15 in position during the installation of the radiator, and the load of the radiator is preferably carried on the carrying member 15 and not on the clamping bolt 17.

In accordance with this invention we employ 40 a top hung radiator bracket which can be employed in conjunction with all types of radiators now on the market irrespective of their size, so that the bracket is standard for all sizes and it is not necessary for the dealer 45 to carry in stock a number of different parts in order to adapt the radiator bracket to carry a special size or type of radiator.

It is unnecessary in this invention to employ the usual and conventional tie rod as the 50 radiator is supported at its upper portion to the radiator bracket and bears against the aligning member. If, however, in any special case it is desired to use a tie rod, it can be connected with the aligning member 21 which in such case would be apertured to receive the hook of the tie rod.

Attention is directed to the fact that in 30 applicants' invention the radiator is supported eccentrically of its hub. The member secured to the radiator cooperates with the radiator supporting member 10 in such a manner that the radiator is supported and retained in its aligned position and it is also anchored 35 in such position due to the cooperation be-

tween the plate 15 and the plate 10. The channel 5 forms a bolt carrier in which the bolt 9 is rotatably adjusted to affect the vertical adjustment of the radiator supporting member 10.

70 It will now be apparent that we have devised a new and useful radiator bracket which embodies the features of advantage enumerated as desirable in the statement of the invention and the above description, and while we have 75 in the present instance, shown and described a preferred embodiment thereof which will give in practice satisfactory and reliable results, it is to be understood that this embodiment is susceptible of modification in 80 various particulars without departing from the spirit or scope of the invention or sacrificing any of its advantages.

Having thus described our invention what we claim as new and desire to secure by Letters Patent, is:—

85 1. In a radiator bracket, a bracket portion adapted to be secured to a wall, a radiator supporting member adapted to pass between tubes of a radiator and rotatably mounted on said bracket portion, and a member secured to the radiator tubes, said radiator supporting member having a seat in its upper face to receive the member secured to said radiator tubes and thereby support and anchor the radiator in aligned position.

90 2. In a radiator bracket, a bracket portion adapted to be secured to a wall, a radiator supporting member adapted to pass between tubes of a radiator, a threaded bolt carried by said bracket portion, a nut on said bolt, supporting said radiator supporting member and prevented by it from relative rotation with it, and means carried by the radiator tubes adapted to be seated on the upper portion of said radiator supporting member.

95 3. In a radiator supporting bracket, a bracket portion comprising a member adapted to be connected with the wall and provided with a bolt carrier and with a radiator aligning member, a bolt rotatable on said carrier, a nut on said bolt, a radiator supporting member supported on said nut and rotatable on said bolt and having a slot in its upper face, a plate seated in said slot, and means to clamp said plate to the radiator to be supported.

100 4. In a radiator hanger the combination with a wall engaging member and a bracket arm supported on said member, said arm being arranged to project between sections of a radiator, of a plate adapted to be held in predetermined position upon a radiator and to transmit the weight of said radiator to said arm, said plate being formed to removably engage said arm, and means independent of said wall engaging member and arm for securing said plate to the radiator.

105 5. In a radiator hanger, the combination

with a wall engaging member and a bracket arm supported on said member and arranged to project between sections of a radiator, of a carrying member engaging the arches of juxtaposed sections and resting on and removably engaging said arm.
